CLAIM

The ornamental design for a hitch pin device, substantially as shown and described.

DESCRIPTION

FIG. 1 is a front and top perspective view of a hitch pin device showing my new design;

FIG. 2 is a front elevation view thereof;

FIG. 3 is a right side elevation view thereof;

FIG. 4 is a rear elevation view thereof;

FIG. 5 is a left side elevation view thereof;

FIG. 6 is a top plan view thereof;

FIG. 7 is a bottom plan view thereof; and,

FIG. 8 is a rear and bottom perspective view thereof.

The broken line showing of the cotter pin is provided for the purposes of illustrating environmental structure and forms no part of the claimed design.
